UNITED STATES PATENT OFFICE

DAVID S. JACOBUS, OF JERSEY CITY, NEW JERSEY, ASSIGNOR, BY MESNE ASSIGNMENTS, TO FULLER LEHIGH COMPANY, A CORPORATION OF DELAWARE

AIR COOLED FURNACE AND METHOD OF OPERATING THE SAME

Application filed June 17, 1925, Serial No. 37,641. Renewed January 13, 1931.

My present invention relates to furnaces, and particularly those in which high furnace temperatures are used and in which the walls are cooled by air.

5 My invention will be best understood from the following description and the annexed drawing, in which the figure shows a vertical longitudinal section of a steam boiler and its furnace embodying one form 10 of my invention and with which my novel method may be practiced.

In the illustrative embodiment, the furnace chamber 10 is made up as usual of approximately vertically disposed walls arranged to provide a furnace chamber substantially rectangular in cross-section. A roof 11 has one or more powdered fuel burners 12 extending therethrough, the fuel being projected downward and the burning 20 gases turning upward to the gas exit at the right of the chamber in the figure. Over the furnace gas exit is a water tube steam boiler of a typical form from which, after the gases have passed back and forth across 25 the water tubes, the gases leave through the gas exit 13.

The front furnace wall 14 is provided with a plurality of air passages 15 leading from vertically disposed air passages 16 directly into the furnace chamber adjacent the downcoming fuel. Beneath the furnace bottom 17 is an air passage or passages 18 receiving air from a duct 19, the passage 18 communicating with the lower part of the 5 passage or passages 16.

The side and rear walls of the furnace chamber 10 are made up in sections, in the illustrative embodiment, each section being provided with a plurality of horizontal air 10 passages 20 leading from the rear wall through the side walls to the air passage 16. The particular construction of the sectional furnace wall is no part of my present invention, but is more fully described in my copending application Serial No. 42,367 filed July 9, 1925 and further description thereof will, therefore, not be necessary, it being understood that these horizontally disposed air passages may be formed in any desired manner.

Each of the horizontal passages 20 connects through the rear wall with a duct 21, each of which, in turn, connects with a duct 19.

The gases from the flue 13 pass through 55 an air heater and from thence to a smoke outlet 22. The air heater is made up of a first part 23 and a second part 24, the air to be heated being forced by the fan 25 through the duct 26 into the lower part of 60 the air heater 24 and, after passing back and forth over the heating surface thereof, entering a duct 27 which communicates with the duct 19 and also with a duct 28 leading to a fan 29, the fan 29 being connected by 65 a duct 30 with the upper part of the air heater 23. A damper 31 in the duct 28 may be used to regulate the flow of air to the fan 29. From the air heater 23, the heated air flows through the duct 32 to a duct 33 extending across the front of the boiler and communicating with each of the powdered fuel burners 12.

With the arrangement described, air is forced by the fan 25 through the heater 24 75 and some of such air passes through the duct 19 into the horizontal ducts 20, this air cooling the side and rear walls of the furnace chamber 10 and, of course, becoming heated thereby, so that when it enters the passage 16, it will be relatively hot. Some of the air from the duct 19 will flow directly into the passage 16 through the duct 18 beneath the furnace wall 17.

Some of the air from the heater 24 will 85 pass to the fan 29, and from thence will be forced through the first air heater 23 and from thence to the burners 12. It will be seen that the air supply to the burner will be highly heated because such air has passed through the entire air heater, whereas the part which is supplied to the duct 19 passes through only a part of the air heater and that the coolest portion of such air heater. 90

95 While the air supplied to the ignited powdered fuel stream through the air passages 15 will receive additional heat from the furnace walls, I preferably operate the furnace so that the air supplied to the burn- 100

ers 12 through the duct 33 will be hotter than the air through the passages 15.

In the illustrative embodiment, the furnace chamber is provided with the usual 5 slag screen connected to the water circulation of the boiler, but since this is no part of my present invention, further description thereof will be unnecessary.

It will be understood that the embodiment 10 of my invention may be widely varied and that some of the parts of my invention may be used independently of other parts. It will also be understood that each of the air ducts may be supplied with dampers, if desired, to 15 control the amount of air flowing through the several passages. It will also be understood that while I have shown my invention applied to a powdered fuel furnace, some of its features may be used with other forms of 20 fuel. The fan 29 may be omitted, if desired, but I prefer to use such a fan so that air delivered to the burners can be under higher pressure than the air in the duct 19 and by placing the fan 29 in the position shown, 25 the air handled by it is at a lower temperature and, therefore, of less volume than it would be if the fan were in the duct 32.

I claim:—

1. A furnace chamber having cooling air 30 passages in the walls thereof and communicating with said chamber, a fuel burner to supply fuel to said chamber, a first and a second air heater contacted in the order named by the furnace gases, ducts to lead heated air 35 from the second air heater to said cooling air passages, and ducts to lead heated air from said second air heater to the first air heater and from thence to said burner.

2. A furnace chamber having cooling air 40 passages in the walls thereof and communicating with said chamber, a fuel burner to supply fuel to said chamber, a first and a second air heater contacted in the order named by the furnace gases, ducts to lead heated air 45 from the second air heater to said cooling air passages, ducts to lead heated air from said second air heater to the first air heater and from thence to said burner, and a damper to control the flow of air from the second air 50 heater to the first air heater.

3. A furnace chamber having cooling air 55 passages in the walls thereof and communicating with said chamber, a steam boiler contacted by the gases from the furnace, a first and a second air heater in the boiler waste gas flue and contacted successively by the waste gases in the order named, a fuel burner for said furnace chamber, a duct to lead heated air from said first air heater to 60 said burner, and a duct to lead heated air from said second air heater to said passages.

4. A furnace chamber having cooling air 65 passages in the walls thereof and communicating with said chamber, a steam boiler

contacted by the gases from the furnace, a first and a second air heater in the boiler waste gas flue and contacted successively by the waste gases in the order named, a fuel burner for said furnace chamber, ducts to 70 lead heated air from said second air heater to said first air heater and from said first air heater to said burner, and a duct to lead heated air from said second air heater to said passages.

5. A furnace chamber having cooling air 75 passages in the walls thereof and communicating with said chamber, a steam boiler contacted by the gases from the furnace, a first and a second air heater in the boiler waste gas flue and contacted successively by the waste gases in the order named, a fuel burner for said furnace chamber, ducts to 80 lead heated air from said second air heater to said first air heater and from said first air heater to said burner, a fan in said ducts between the first and the second air heaters, and a duct to lead heated air from said second air heater to said passages.

6. The method of operating a furnace 85 which comprises projecting into the furnace a stream of fuel, igniting and burning said fuel in the furnace, extracting heat from the waste gases and heating air therewith, supplying said heated air to the fuel 90 adjacent its place of ignition, extracting some of the remaining heat from the waste gases and heating air therewith, and supplying said last named air to the furnace where the fuel is burning.

7. The method of operating a furnace 95 which comprises projecting a stream of fuel into the furnace, igniting and burning the fuel therein, extracting heat from the waste gases and heating air therewith, mixing said air with the fuel as it is projected into the furnace, extracting some of the remaining heat from the waste gases and heating air therewith, and directing said last named air 100 into the furnace adjacent the stream of burning fuel.

8. The method of operating a furnace 105 which comprises projecting a stream of fuel into the furnace, igniting and burning the fuel therein, extracting heat from the waste gases and heating air therewith, mixing said air with the fuel as it is projected into the furnace, extracting some of the remaining heat from the waste gases and heating air 110 therewith, directing said last named air into the furnace adjacent the stream of burning fuel, and at a plurality of places spaced along the length of said stream.

DAVID S. JACOBUS.
